UNITED STATES PATENT OFFICE

147,516

DESIGN FOR A HOBBYHORSE

George W. Walker, Pleasant Ridge, Mich., and Basil G. Baldwin, Euclid Beach Park, Ohio, assignors to B & V New Products Company,
Rochester, N. Y., a firm composed of Basil G.
Baldwin and Carl Voehringer

Application July 11, 1946, Serial No. 131,502

Term of patent 7 years

(Cl. D34—15)

To all whom it may concern:

Be it known that we, George W. Walker and Basil G. Baldwin, citizens of the United States, residing respectively at Pleasant Ridge, in the county of Oakland and State of Michigan, and at Euclid Beach Park, in the county of Cuyahoga
and State of Ohio, have invented a new, original,
and ornamental Design for a Hobbyhorse, of which the following is a specification, reference being had to the accompanying drawing, forming part thereof.

In said drawing, Fig. 1 is a side view of a hobby horse showing our new design; Fig. 2 is a top plan view thereof; Fig. 3 is a front view thereof;
and Fig. 4 is a rear view thereof. The dominant features of the design reside in those portions thereof shown in full lines.

We claim:
The ornamental design for a hobbyhorse, substantially as shown and described.

GEORGE W. WALKER.
BASIL G. BALDWIN.
